UNITED STATES PATENT OFFICE.

CHARLES H. BOWEN, OF WASHINGTON, DISTRICT OF COLUMBIA.

ELECTRIC-CABLE SUPPORT.

SPECIFICATION forming part of Letters Patent No. 395,207, dated December 25, 1888.

Application filed August 17, 1888. Serial No. 283,022. (No model.)

To all whom it may concern:

Be it known that I, CHARLES H. BOWEN, a citizen of the United States, residing in Washington city, in the District of Columbia, have 5 invented certain new, useful, and important Improvements in Electric-Cable Supports, of which the following specification is a description sufficient in law.

This invention provides for supporting, insulating, and grouping the cables of a system of underground or elevated lines in such convenient manner that the respective lines or systems may be readily put up and changed or rearranged, as occasion may require, with 15 little labor and without serious inconvenience or interruption of business.

The above-mentioned objects are attained by the means illustrated in the accompanying drawings, in which—

20 Figure 1 represents an end elevation of an improved insulated cable-support. Fig. 2 represents a longitudinal vertical section thereof; Fig. 3, a side elevation of the sleeve B detached, showing a bayonet-joint; Fig. 4, a side elevation of the sleeve B and a locking-joint; Fig. 5, a transverse section of a street, showing this invention applied to a subterranean system of cables; and Fig. 6, a modification of the invention, wherein the cable is extended 25 through tubes provided with lateral branches for carrying the cable-wires to various points, but supported the same as separate cables. Fig. 7 illustrates an end view of the hanger or support, recess, and the insulator, showing the position of the lugs when the insulator is in place embracing the wire or cable. Fig. 8 represents a longitudinal sectional view of the hanger and insulator inclosed with the embraced cable in side elevation. Fig. 9 represents a detached view of the insulator, showing 30 projections thereon; and Fig. 10, a detached view of the insulator, showing the lugs and the means of connecting the divided sections.

45 Referring to the drawings, the letter A indicates a support or pendant, constructed in the nature of an annular sleeve, which is slotted, as shown by the letter a. The said pendants are constructed of metal, wood, or 50 glass, but preferably of insulated material, and they form the support for an insulated sleeve.

B indicates a divided sleeve, which fits within the support A. The sleeve may taper slightly from one end to the other, and the interior of the support A may be correspondingly tapered, so as to form a seat for the said sleeve B.

The sleeve B is constructed of glass, asbestos, or other insulated material, and may have 60 a flat hinged or interlocking joint, the latter form of construction being shown in Fig. 4 at c d. The outer surface of the sleeve B and inner surface of the support A are constructed with a bayonet-joint, e g.

The sleeve B projects beyond the support A in order to prevent the cable from coming in contact with the edges of the support, and thereby impairing insulation. The sleeve B is provided at the projecting end with lugs b² 70 and the hanger or support with longitudinal internal recesses, b³, through which the lugs are passed, and the end of the support is formed with inclined facets b⁴, against which the lugs or projections bear by turning the insulator. This binds the insulator and causes it securely to hold the wire or cable.

The support A may be hinged, hung from, or otherwise secured to a suitable sleeper or bar either below the ground or above it. A 80 series of these supports are secured along the route of the cable, which is secured in position within each support by passing it through the slot a, then placing the sleeve B around the cable, and then by uniting the support and its sleeve, as clearly shown in Fig. 2, thus holding and insulating the cable.

Where a limited number of cables are employed it is preferred to arrange them side by side, as shown in Fig. 5, in which is shown an 90 underground system, the cables being arranged in tunnels below the surface of a street. Where a larger number of cables are necessary, however, there is employed a series of brackets, E, which are secured to dependent standards F, attached to the roof of the tunnel, and the supports A are secured to the dependent brackets. To insure the insulation of the respective lines and prevent induction, insulating-partitions M are located 95 between the lines.

Instead of supporting the brackets from dependent standards, they may be suspended directly from the sleeper with insulated sec-

tions M between them, whereby the brackets themselves will be insulated.

Any number of tunnels may be arranged under the roadway, each of which may be devoted to a particular system of cables. For instance, one tunnel may be occupied by the cables supplying electric lights, while in other tunnels may be lines or cables for electric motors, telegraphs, and telephones.

- 10 In the modification of my invention shown in Fig. 6 of the drawings the supports A carry the cable-holders G, constructed of iron, timber, or terra-cotta, which are preferably tubular, and within which are arranged divided 15 glass or asbestos sections I, through which the cables pass, thus securing a strong permanent line which is thoroughly insulated. At desired intervals the sections are provided with short lateral branches K, through which the 20 cables may be carried out to any desired point.

In one modification (shown in Fig. 5) the lower series of tubular sections are suspended from the upper section and from each other 25 by means of links L, of glass, hard rubber, or other insulating material, which may be divided and hinged at L' and provided with locking devices m^2 for quick adjustment.

The tunnels are constructed of brick or 30 stone, or some such material, with supporting or division walls of any depth or width, according to the number of wires or cables to be inserted, and the structure has man-holes at intervals for examining the wires, for re- 35 pairs, or for other purposes. The coverings of arches are to be non-metallic, except the strengthening devices, as "stars," braces, bands, or clamps from one portion to the other of the subway.

40 While this invention is shown as applied to tunnels under the pavements of a street, it is evident that it may be applied through the sewers of a street or to elevated supports above ground with equal advantage. It is 45 evident, also, that the tunnels when constructed for my improved cable system may also be trapped and utilized as water-drains, as shown in Fig. 5.

Besides the advantages of thorough insulation and perfect support of the cables, the 50 great advantage of my system consists in the facility with which the lines or cables may be put up, taken down, or rearranged. This is owing to the novel construction of the slotted 55 supports A and the divided sleeves B, which permit the cables to be securely fastened in place or quickly removed, leaving the supports ready to receive another cable, without cutting, breaking, or destroying any portion 60 of the cable or its supporting devices. The novel construction of the hangers also permits the cables to be readily carried to any convenient point without detaching the hangers and without interruption to business. 65 Another advantage due to my improved cable system is that the cables can be handled without skilled labor, as there are no connections

to be made requiring the services of a skilled mechanic; hence a material item of expense is saved in starting and maintaining the line. 70

While I have shown, but only for purposes of illustration, electric-light, dynamo, telegraph, and telephone systems side by side, it is assumed that in the construction of any one system, as the telephone, that the wires 75 will be laid far enough from the wires of the telegraph or any other system as to prevent induction from stronger currents. Each system must be built so that its currents will not be unfavorably affected by the currents of 80 neighboring systems.

Having thus fully described my invention, what I claim, and desire to secure by Letters Patent, is—

1. The combination, with the slotted supports, of the cable-holders provided with lateral extensions through which the cable or conductors may be carried off, substantially as specified. 85

2. A system of cable-supports composed of 90 a main support or a hanger having a removable sleeve, and a series of similarly-constructed supports grouped or connected with the main support, substantially as specified.

3. A portable or detachable support for 95 electric wires or cables having a conical interior and a longitudinal slot, in combination with an insulator having a conical exterior which incloses and holds the wires or cables, as described. 100

4. A support constructed with a conical interior for the reception of a conical insulator, having a groove or recess above and an open slot below in order to permit the insertion of the insulator which has inclosed the wires or 105 cable, as described.

5. A locking device for an insulator, consisting of the lugs on the sleeve constituting the insulator, in combination with the inclined or beveled ends of the support, as described. 110

6. A slotted insulated hanger or support conical in length, in combination with a divided insulated sleeve, also conical in length, fitted therein and locked externally, and thereby adapted to hold a wire or cable, as 115 described.

7. The combination, with a supporting-hanger having internal recesses, of a divided insulating-sleeve provided with lugs on its outside to engage with the hanger, as described. 120

8. A portable hanger with slot underneath and a groove or recesses on its upper interior surface for the simultaneous passage of the upper and lower lugs and of the conical divided sleeve clear through the conical hanger, whereby said sleeve may be locked in place by turning the lugs upon the beveled surfaces of the hanger, as described. 125
